[57] CLAIM

The ornamental design for a tire, as shown and described.

DESCRIPTION

FIG. 1 is a front-right-top perspective view of a tire showing my new design, it being understood that the tread pattern repeats uniformly throughout the circumference of the tire; FIG. 2 is a front elevational view thereof, the opposite side being a mirror image; FIG. 3 is a right elevational view thereof, the opposite side being a mirror image; and, FIG. 4 is an enlarged fragmentary developed plan view thereof showing the tread pattern in greater details.
